[57] CLAIM

The ornamental design for a toy block, as shown and described.

DESCRIPTION

FIG. 1 is a perspective view of the invented toy block, showing the left side, front, and top of my new design.

FIG. 2 is a perspective view of the toy block of FIG. 1, rotated 90 degrees, and showing the left side, front and bottom thereof.

FIG. 3 is a perspective view of the toy block of FIG. 1 taken from the exact opposite direction as FIG. 1.

FIG. 4 is a front view of the toy block shown in FIG. 1.

FIG. 5 is a right side view of the toy block shown in FIG. 1.

FIG. 6 is a left side view of the toy block shown in FIG. 1.

FIG. 7 is a back view of the toy block shown in FIG. 1.

FIG. 8 is a top view of the toy block shown in FIG. 1; and,

FIG. 9 is a bottom view of the toy block shown in FIG. 1.
